United States Patent Office

Des. 212,019
Patented Aug. 20, 1968

212,019

EXERCISER

Albert Schawalder, Brugg, Bern, Switzerland, assignor to Monty MacLevy, New York, N.Y.

Filed July 27, 1967, Ser. No. 8,036

Term of patent 14 years

(Cl. D34—5)

Fig.3

FIG. 1 is a front perspective view of my new design as it would appear while in use in a position tilted to one side with the user, shown in phantom, inclined to one side;

FIG. 2 is a front perspective view of my new design as it would appear while in use in a position tilted to the opposite side with the user, shown in phantom, inclined to the opposite side;

FIG. 3 is an enlarged front perspective view of my new design in the neutral position with the user omitted.

I claim:

The ornamental design for an exerciser, as shown and described.
